UNITED STATES PATENT OFFICE

DELBERT BAKER, OF TULSA, OKLAHOMA, ASSIGNOR OF ONE-HALF TO JOHN J. FRIEL,
OF TULSA, OKLAHOMA

WIRE-LINE SOCKET

Application filed April 20, 1929. Serial No. 356,672.

This invention relates to wire line sockets and more particularly to the construction of the sockets employed for connecting wire cable to the drilling tools of well drilling apparatus. In accordance with the present practice, the wire line socket employed is usually connected to the wire line by introducing the wire line through a smaller to a larger bore of the socket and then surrounding 5 the inner end of the wire line with babbitt, which is allowed to set thereabout. The Babbitt metal provides only a support and will not permit the swiveling at the connection of the wire line and socket as is necessary to eliminate the twisting action resulting 10 from the alternately tightening and loosening of the strands of the wire line. This method of providing connection is objectionable in that replacement of the connection 15 which must be made every thirty-six or forty-eight hours of drilling time requires a considerable time. The old babbitt must be melted out, the cable cut and a re-babbinning operation performed. This naturally requires 20 considerable time during which the drilling operation is interrupted and the crew idle.

Accordingly, an important object of the invention is to provide a structure which enables a swiveling connection between the wire line and socket, and which permits a much more rapid replacement of the wire line when such replacements become necessary.

A further object of the invention is to produce an apparatus of this character which may be employed in the present type of socket and which may be very readily and cheaply produced.

These and other objects I attain by the construction shown in the accompanying drawings wherein for the purpose of illustration I have shown a preferred embodiment of my invention and wherein:—

Figure 1 is a vertical sectional view 45 through a wire line socket having cable connected means constructed in accordance with my invention;

Figure 2 is a vertical sectional view 50 through the plug removed;

Figure 3 is a section on line 3—3 of Figure 1;

Figure 4 is a plan view of the plug;

Figures 5 and 6 are a plan and side elevation of a wedge for separating the connector 55 sections.

Referring now more particularly to the drawings, the wire line socket comprises a body 10 adapted at its lower end as indicated at 11, for engagement with the tool. This 60 body has extending upwardly therein from its lower end a bore 12, the upper end of which is in the form of an upwardly tapering seat 13. The upper end of the body has a reduced extension 14, having a smaller bore 15 extending axially therethrough and communicating 65 at its lower end with the upper end of the main bore 12. The construction recited is that ordinarily provided in wire line sockets.

In accordance with my invention, I dispose 70 within the bore 12 a sleeve 16, the upper end of which is slantingly cut, as indicated at 17, and adapted to have swiveling engagement against the seat 13 at the upper end of the main bore. This sleeve has an upwardly 75 tapering bore 18, and disposed within this bore is a plug 19 having a corresponding taper, and having at its lower end which projects from the lower end of the sleeve when the plug is fully seated, an enlarged 80 head 20. This plug is formed with a spiral groove 21, having at least one complete convolution, the upper end of this groove communicating with a cove 22 extending to the approximate center of this smaller upper end. 85 This groove is of slightly less depth than the diameter of the wire line, and in use of the apparatus, the wire line is passed through the openings 15 and 12 through the bore of the sleeve, and then wound in the groove 21 of 90 the plug after which the plug is inserted in the sleeve, and the upper end of this sleeve caused to engage seat 13 by the pull on the wire line.

It will be obvious that the frictional engagement of the wire line with the plug will cause the plug to more firmly seat in the sleeve, and that the frictional engagement of the wire line with the sleeve and plug will prevent any longitudinal movement of the 95 100

wire line, so that the wire line is securely held and at the same time provided with a swivel mounting.

In removing the plug for replacement the wire line may be cut and the plug and sleeve separated by exerting spreading force between the lower end of the sleeve and the head 20 of the plug. This may be conveniently accomplished by use of a wedge such as shown in Figure 6 which has a slot 23 to receive the plug immediately above the head. The lower end of sleeve 16 is preferably slightly slantingly cut, as indicated at 24, in order that the strain applied by this wedge 15 may be applied axially to the sleeve and plug.

Since the construction herein illustrated is capable of a very considerable range of change and modification without in any manner departing from the spirit of the invention, I accordingly do not limit myself to such specific structure except as herein-after claimed.

I claim:—

1. In combination with a wire line socket 25 having a main bore and a reduced bore for the entrance of wire line to the main bore, the junction of said bores providing a seat, a sleeve engaged against said seat, the sleeve having a bore, and a plug inserted in the bore 30 of the sleeve and having an exterior helically extending groove for the reception of the wire line.

2. In combination with a wire line socket having a main bore and a reduced bore for 35 the entrance of wire line to the main bore, the junction of said bores providing a seat, a sleeve engaged against said seat, the sleeve having a bore, and a plug inserted in the bore of the sleeve and having an exterior helically extending groove for the reception 40 of the wire line, said groove being of less depth than the diameter of the wire line.

3. In combination with a wire line socket having a main bore and a reduced bore for 45 the entrance of wire line to the main bore, the junction of said bores providing a seat, a sleeve engaged against said seat, the sleeve having a bore, and a plug inserted in the bore of the sleeve and having an exterior helically extending groove for the reception 50 of the wire line, the plug and bore of the sleeve having corresponding upward tapers.

4. In combination with a wire line socket having a main bore and a reduced bore for 55 the entrance of wire line to the main bore, the junction of said bores providing a seat, a sleeve engaged against said seat, the sleeve having a bore, and a plug inserted in the bore of the sleeve and having an exterior helically 60 extending groove for the reception of the wire line, the plug and bore of the sleeve having corresponding upward tapers, the lower end of the plug having a shoulder confronting the lower end of the sleeve.

5. In combination with a wire line socket

having a main bore and a reduced bore for the entrance of wire line to the main bore, the junction of said bores providing a seat, a sleeve engaged against said seat, the sleeve having a bore, and a plug inserted in the bore of the sleeve and having an exterior helically extending groove for the reception of the wire line, the lower end of the plug having a shoulder confronting the lower end of the sleeve.

6. In combination with a wire line socket having a main bore and a reduced bore for the entrance of wire line to the main bore, the junction of said bores providing a seat, a sleeve engaged against said seat, the sleeve having a bore, and a plug inserted in the bore of the sleeve and having an exterior helically extending groove for the reception of the wire line, the plug and bore of the sleeve having corresponding upward tapers, the lower end of the plug having a shoulder confronting the lower end of the sleeve, the lower end of the sleeve being slantingly cut.

In testimony whereof I hereunto affix my signature.

DELBERT BAKER.
